UNITED STATES PATENT OFFICE.

LEMUEL J. HUSTED, OF KANSAS CITY, MISSOURI.

FIRING INSTRUMENT FOR MARINE MINES.

1,387,722.

Specification of Letters Patent. Patented Aug. 16, 1921.

Application filed October 20, 1917, Serial No. 197,724. Renewed April 21, 1921. Serial No. 464,007.

To all whom it may concern:

Be it known that I, LEMUEL J. HUSTED, a citizen of the United States, residing at Kansas City, in the county of Jackson and State 5 of Missouri, have invented certain new and useful Improvements in Firing Instruments for Marine Mines, of which the following is a full, clear, and exact description, such as will enable others skilled in the art to 10 which it appertains to make and use the same.

The invention relates to magnetically operated electrical circuit closing mechanism for firing and exploding marine mines and 15 seeks to provide a simple and effective instrument which can be connected to or directly mounted upon the marine mine so that when a vessel approaches the mine, the magnetic repulsion or attraction of the vessel 20 will operate the instrument and close the electrical circuit and fire and explode the mine.

The most approved type of marine mine employed by the United States and other 25 countries requires actual contact of the mine by the vessel in order to fire the mine, and a still greater objection lies in the recognized fact that the vessel can strike the mine and not fire and explode it, owing to the further 30 fact that the vessel must strike the mine in a position and under conditions that will roll and rotate the mine at least several degrees before the explosion of the mine can result.

35 Marine mines are usually of spherical shape and buoyant and are attached by a cable to an anchor that rests on the bottom of the sea so that the mine is submerged to a considerable depth, this depth being regulated by mechanism attached to the anchor. The enemy vessel for which many mines are placed is the submarine, and as these vessels are usually of cylindrical shape it can readily be seen that when the greatest horizontal diameter of the vessel is at a slightly 45 greater or less depth than the greatest horizontal diameter of the mine, the vessel can strike the mine and not rotate or fire and explode it.

50 It is essential for the successful destruction of the submarine and other enemy vessels that the mine be provided with an efficient means that will fire and explode it when the vessel approaches sufficiently near 55 to be destroyed by the explosion of the mine.

It has been stated on undisputable authority that the usual mine now employed will destroy a submerged submarine vessel if exploded within fifty feet of the vessel and 60 that the explosion of the mine within one hundred feet of a submerged submarine will injure the latter so that it must rise to the surface where it becomes an easy victim of 65 gun fire.

The magnetic field of a submarine is known by actual test to be sufficient to oscillate a magnetic needle at distances of fifteen to thirty feet and in some cases this field is believed to be much greater. 70

The present invention seeks to provide an improved instrument which can be mounted directly upon or attached to the usual marine mine so that when a submarine or other vessel approaches within the distance 75 of the magnetic field of the vessel the instrument will be actuated by the magnetic attraction or repulsion of the vessel and the electrical firing circuit will be closed and the mine fired and exploded and the vessel 80 destroyed.

By firing the mine without contact therewith and at some distance from the vessel a great saving in the number of mines required to protect or attack a certain area 85 will be effected and vessels will be destroyed that are submerged to a greater or less depth than the mine, owing to the angles along which magnetic force is known to attract or repulse. 90

With these and other objects in view, the invention consists in the features of construction, combinations and arrangements of parts hereinafter set forth and more particularly pointed out in the appended claims, 95 the accompanying drawings illustrating certain forms of the invention.

In the drawings:

Figure 1, is a vertical sectional view with certain minor parts shown in full view of 100 the preferred form of the improved mine firing instrument taken on line 1—1 of Fig. 2.

Fig. 2 is a horizontal sectional view taken on line 2—2 of Fig. 1. 105

Fig. 3, is an enlarged fragmentary plan view with certain parts removed and others broken away.

Fig. 4, is an enlarged fragmentary inverted sectional view taken on line 4—4 110 of Fig. 1.

Fig. 5 is an enlarged fragmentary hori-

zontal sectional view taken on line 5—5 of of the form shown in Fig. 24, with certain 65 parts broken away.

Fig. 6, is an enlarged fragmentary vertical sectional view taken on line 6—6 of 5 Fig. 1.

Fig. 7 is an enlarged fragmentary vertical sectional view of the upper bearing pin and connections taken on line 7—7 of Fig. 1.

Fig. 8 is an enlarged fragmentary vertical sectional view of the lower post taken 10 on line 8—8 of Fig. 1.

Fig. 9 is an enlarged fragmentary vertical sectional view of the lower needle hub taken on line 9—9 of Fig. 1, the upper needle 15 hub being of duplicate form and construction only smaller.

Fig. 10 is a view in elevation with certain parts broken away, of a modified form of the improved mine firing instrument.

20 Fig. 11 is a plan view with the cover broken away to show the interior construction.

Fig. 12 is a vertical sectional view taken on line 12—12 of Fig. 11, with certain small 25 parts shown in full view.

Fig. 13 is an enlarged fragmentary horizontal view taken on line 13—13 of Fig. 12.

Fig. 14 is an enlarged fragmentary vertical view taken on line 12—14 of Fig. 16.

30 Fig. 15 is an enlarged fragmentary vertical sectional view taken on line 15—15 of Fig. 16.

Fig. 16 is a fragmentary duplication of Fig. 12, excepting that certain minor parts 35 are modified and differ therefrom.

Fig. 17 is an enlarged fragmentary vertical sectional view taken on line 17—17 of Fig. 16.

Fig. 18 is a view in elevation of a further 40 modified form of the improved marine mine firing instrument with certain parts broken away to show the construction.

Fig. 19 is vertical sectional view of the upper part of Fig. 18, taken on line 19—19.

45 Fig. 20 is a fragmentary enlarged broken plan view of this modified form.

Fig. 21 is a fragmentary enlarged horizontal sectional view taken on line 21—21 of Fig. 19.

50 Fig. 22 is an enlarged plan view of the magnetic needle employed in the form illustrated in view 18 to 22 inclusive, this construction being duplicate in all the forms illustrated in views 18 to 27 inclusive.

55 Fig. 23 is an enlarged vertical sectional view taken on line 23—23 of Fig. 19.

Fig. 24 illustrates a further modified form of construction from that shown in Figs. 18 to 23 inclusive, the view corresponding to 60 the vertical sectional view Fig. 19 but with minor changes in construction.

Fig. 25 is an enlarged inserted sectional view taken on line 25—25 of Fig. 24.

Fig. 26 is an enlarged fragmentary view

of the form shown in Fig. 24, with certain 65 parts broken away.

Fig. 27 is an enlarged fragmentary sectional view taken on line 27—27 of Fig. 26.

Fig. 28 is a plan view of a still further modified form of the marine firing instrument, with the cover plates broken away to show the interior.

Fig. 29 is a vertical sectional view taken on line 29—29 of Fig. 28.

Fig. 30 is a fragmentary enlarged sectional 75 view taken on line 30—30 of Fig. 29.

Fig. 31 is an enlarged fragmentary plan view of certain parts shown in Fig. 28.

The containing box, 1 gimble ring 2, and hingedly connecting suspension pins 3 and 4 80 are of ordinary construction, and are for the purpose of supporting the instrument in a true level and vertical position as a mariner's compass.

The bowl 5 is of cylindrical shape pref- 85 erably true and smooth throughout the in- terior thereof so that a rotary motion will not rotate the liquid 6 and parts sensitive to

magnetic attraction, as will be hereinafter 90 described, the bowl being hingedly connected to the gimble ring 2 by the pins 4, and the gimble ring hingedly connected to the box 1 by the pins 3, it being understood that the

instrument is attached to a marine mine and that the mine will, owing to the action of the 95 waves when the water is rough as during a storm, toss to and fro and be slightly rotated. The attachment of the instrument to the mine however, is no part of the present invention.

100 The cover plate 7 rests upon the bowl 5 and is clamped thereto, sufficiently tight to hold liquid, by the ring 8 and the screws 9, it being obvious that if both the plate and bowl are true and smooth the joint will not leak, there would be no invention however in inserting a common and well known form of gasket between the cover and bowl.

105 Projecting upward from the cover plate 7 is the pipe 10, which is as shown in the pre- 110 ferred form integral with the plate, there being no advantage in this form in separating the pipe and making it adjustable as in the modified forms, for the reason that this pipe is not lengthened or shortened to ad- 115 just the distance between the magnetic needles, while in the modified forms the pipe is adjusted according to the distance between the needles as will appear hereinafter.

120 The pipe 10 is threaded on the exterior and fitted preferably air tight by the cap nut 11 preferably of insulating material, the in- terior of the pipe also being threaded and fitted with the threaded ring 12 which is pro- vided with the cross bar 13 integral with the 125 ring.

The ring 14 rests loosely upon the bottom 15 of the bowl 5, the plate 16 resting in turn

loosely on the ring, and from the plate projects upward the post 17, the jewel 18 resting upon the post and supporting the ordinary hub 19, to which is secured the ordinary 5 lower compass needle 20.

Loosely fitting the hub 19 is the sleeve 21 which is provided with the slot 22, the pin 23 rigid with the hub and projecting therefrom, fitting within this slot and connecting 10 the hub and sleeve rotatively but allowing the sleeve to be otherwise free on the hub so that the needle 20 can slightly oscillate transversely upon the post resulting in the 15 needle being more responsive to the earth's poles and other magnetic influence.

Fitting loosely in the sleeve 21 so that the distance inserted in the sleeve can be adjustable, but held rigid by the screws 24, is the stem 25 which is provided with the 20 enlarged portion 26, the braces 27 being secured to this enlarged portion of the post by the rivet 28, the lower frame member 29 resting upon the braces and being secured thereto by the rivets 30, this latter member 25 being bent upward at 31 and flanged outward at 32 and having secured thereto by the rivets 33, the frame member 34, the frame member 35 in turn being secured to the latter member by the rivets 36.

30 The stem 25 has rigidly secured thereto, the post 37, the hub 38 resting on the latter and supporting the upper compass needle 39, the needle and hub and post being a duplication of the post 17, hub 19 and the needle 20 excepting that they are smaller, as it is essential to employ an upper needle of smaller dimensions than the lower needle so that the upper needle will not prevent the lower needle from always pointing approximately north and south, and so that the lower needle will possess sufficient magnetic influence to retain the north and south position and reverse the poles of the upper needle, it being understood that if both needles 45 were of the same dimensions and degree of magnetism that one would point approximately northwest and southeast and the other would point approximately northeast and southwest.

50 The stem 40 is fitted to the upper needle hub 38 in duplicate manner as the sleeve 21 is fitted to the lower needle hub 19, and it is maintained in relatively fixed position with the upper needle 39, the latter needle and 55 the stem 40 being free constructively to rotate upon the upper post 37, but the upper needle is normally held in alinement with the lower needle by magnetic influence.

The frame 35 is provided with the insulating connectors 41, and the stem 40 is provided with the insulating sleeve 42 so that no leakage of electrical energy can occur through the liquid 6.

Extending upward from the upper stem 60 40 through the upper frame 35 and through

the crossbar 13 of the threaded ring 12 is the bearing pin 43, the pin forming a rotary bearing in the crossbar, while to the crossbar is connected by the screw 44 the brush 45, making electrical connection from the 70 threaded ring 12 to the pin. The threaded ring 12 is in electrical connection with the pipe 10 and the screw 46 is provided to connect the wire 47 of the primary ignition circuit. 75

The hub 48 is rigidly secured to the upper frame 35 and in electrical connection therewith, the hub being provided with the insulating bushing 49 which forms a free rotary bearing on the bearing pin 43 so that 80 constructively the frame and pin are free to rotate in the same direction and in opposite directions.

Secured to the crossbar 13 of the threaded nut 12 by the bolt 50 is the insulation 85 bushing 51, upper insulating collar 52, lower insulating collar 53, contact spring 54 and contact brush 55, the brush bearing on the hub 48 and making electrical connection through the brush, the bolt and the spring 90 90 to the screw 56, the latter passing through the insulation material cap nut 11 and being held in position by the nut 57, this screw serving as a connector for the wire 58 of the primary electrical circuit. 95

The cap collar 59 of insulating material is provided on the bearing pin 43 with a slight clearance between the collar and the contact spring 54 so that if the instrument is subjected to violent movements in any direction or turned to inverted position all the interior parts will be held in relative position and not become disarranged. 100

Secured to the frame 35 is the upper contact 60 and the lower contact 61, each of double U shape, and presenting respectively convex contact edges 62 and 63, the latter edge 63 facing upward and the former edge 62 facing downward, the contact edges meeting on approximately the same horizontal 110 plane but slightly separated.

Rigid with the upper stem 40 and the bearing pin 43 is the contact plate 64 with two arms 65 and 66, the arms normally retaining the position shown in Fig. 5, but 115 positioned to pass between the contacts 60 and 61 when either needle is rotated from its normal position of alinement with the remaining needle.

The distance between the magnetic needles 20 and 39 is adjustable by employing various sized rings 14 or by employing various numbers of rings 14 and by adjusting the distance of the stem 25 in the sleeve 21, the view Fig. 1 showing the needles separated to the greatest distance allowable as constructed. 120 125

The wires 47 and 58 are connected in circuit with the usual battery and ignition devices, all of which are of common and well 130

known construction and no part of the present invention, it being understood that the instrument can be attached to the mine in any desired manner, which is no part of the present invention.

When the needles 20 and 39 are subjected to magnetic attraction or repulsion one of the needles will immediately rotate several degrees in one direction and the remaining needle will rotate several degrees in the opposite direction, bringing one of the arms 65 and 66 into contact with one or both of the contacts 60 and 61 and completing the electric circuit through the wires 47 and 58 and firing and exploding the mine.

It is obvious from the foregoing that when a vessel approaches sufficiently near the instrument to rotate the needles in opposite direction, that the circuit will be closed and the mine exploded, and it matters not whether the magnetic force is attraction or repulsion.

In the modified form illustrated in Figs. 10 to 17 inclusive the same principles of construction are employed and the operation is the same as that hereinbefore described, the difference being in that the upper needle 39^a is not submerged in the liquid 6^a, and such minor changes in construction as will conveniently accommodate the removal of the needle 39^a from the liquid 6^a.

The bowl 5^a is of shallow depth and contains only the needle 20^a and accompanying parts practically a duplication of that hereinbefore described, but the cover plate 7^a is provided with an internally threaded pipe 10^a in which is adjustably mounted the nipple 67.

The nipple 67 is secured to the upper housing 68 and is provided with the metal cap nut 69, the nipple being adjustable as to the length extending from the pipe 10^a and the stem 70 being adjustable in the sleeve 21^a so that the housing and all parts contained therein can easily be lowered toward the needle 20^a or raised farther therefrom.

Around the stem 70 is rigidly secured the insulation material 71 to which in turn is secured the hubs 72 and 73, the hub 72 being insulated from the stem and provided with the projecting boss 74. The arms 75 and 76 are rigidly connected to and in electrical connection with the respective hubs 72 and 73 and on these arms are mounted the contact members 77 and 78 respectively.

From the stem 70 electrical connection is made through the contact brush 45^a to the screw 44^a to the cap nut 69 and the housing 68 to the screw 46^a and wire 47^a, while from the boss 74 electrical connection is made through the brush 55^a to the screw 79 and insulated wire 80, the screw 79 being insulated from the cap nut 69 by the insulating collar 81.

Rigidly secured to the hub 73 and pro-

jecting upward therefrom is the post 37 on which rests the jewel 18^a, the latter supporting the needle 39^a and provided with the rigidly depending weight 82 surrounding the post and balancing the needle in level position. This weight is required for the reason that the jewel 18^a is approximately in horizontal alinement with the needle so that the needle will remain steady when the housing 68 is rocked to and fro in either direction.

The contact plate 64^a in this form is secured to the weight 82 and is provided with the arms 65^a and 66^a which on the rotation of either needle a few degrees or the rotation of both needles in opposite direction will contact with the contact members 77 and 78, it being understood that the direction of rotation will determine which of the arms 65^a and 66^a will make the connection.

In Fig. 16 a slight modification from the foregoing is made in that the arms 75^b and 76^b and the contact members 77^b and 78^b are longer than those just described and the contact plate 64^b is secured to the needle hub 38^b above the needle 39^b and the contact arms 65^b and 66^b are longer so as to reach the contact members 77^b and 78^b.

The modified form illustrated in Figs. 18 to 23 inclusive differs from that just described in that a different form of contact members are employed, the housing 68^b and metal cap 69^b being of practically the same construction as that of the form last hereinbefore described.

The sleeve 21^b receives the stem 70^b, and the latter is provided with an enlarged portion 83 from which rigidly projects the contact pins 84 the enlarged portion having mounted thereon, the post 37^b, the needle 39^b 105 resting on the post and provided with the hub 85 from which projects rigidly the contact pin 86 the latter playing between the pins 84 and contacting with one or the other depending on the direction of rotation of the needle 39^b.

The stem 70^b contacts through the bushing 87 to the metal cap 69^b and through the housing 68^b to the screw 88 to which the wire 89 is connected, the needle hub contacting 115 through the pin 90 to the spring plate 91 and to the screw 92 which connects with the wire 93, the upper cover plate 94 being of insulating material.

In the modified form illustrated in Figs. 24 to 27 inclusive, adjustable nipple 67^c opens into the housing 68^c and the cover plate 94^c is provided with the upwardly projecting pipe 95 the latter being fitted with the threaded cap 96 of insulating material.

The sleeve 21^c is provided with the post 37^c on which rests the needle 39^c and has rigidly connected thereto, the frame 97 which passes upward through the needle and is rigidly secured to the hub 98, the latter 130

being provided with the metal bushing 99 and in this metal bushing is rigidly fitted the insulating bushing 100.

- From the frame 97 depends two contact pins 84^a and between these pins is positioned the single contact pin 86^a, the latter pin projecting rigidly from the stem 101 which is fitted loosely on the needle hub 102, but held rigidly against rotation, this stem passing through the hub 98, bushing 99 and insulating bushing 100, and into the bushing 103 which is rigidly secured in the screw 104, and from this screw the wire 105 leads and forms one line of the electrical circuit.
- 15 Fitting loosely around the metal bushing 99 is the contact ring 106 to which is secured the coiled contact spring 107, the latter connecting to the screw 108 from which leads the circuit wire 109.
- 20 The operation of this form is the same as that of those hereinbefore described, the pin 86^a contacting with the pins 84^a as the needle is rotated by magnetic influences the particular pin 84^a employed to complete the connection depending on the direction of the rotation of the needle 39^a.

In Figs. 28 to 31 inclusive is illustrated a slight modification of construction from all the forms hereinbefore described. In this form the adjustable nipple 67^a is secured to the upper housing 68^a and has fitted thereto the metal cap plate 69^a, the latter having fitted rigidly therein the contact bushing 110 in which is rotatively fitted the bushing 111, in which the bushing being rigidly secured in the cupped flange 112 with the contact pins 113 rigidly secured to the flange and projecting upward therefrom.

The bushing 111 and cupped flange 112 are rigidly secured to and insulated from the stem 70^a by the insulating material 114, the stem being adjustably secured in the sleeve 21^a and having mounted thereon the hubbed flange 115 from which projects rigidly upward the needle post 37^a and the contact pins 116, the post being mounted by the single bar needle 39^a.

Loosely fitting around the stem 70^a is the contact ring 117 to which is secured the spring 118, the latter leading to the screw 119, and the screw in turn connecting to the plate 120, the screw 121 connecting the plates 120 and 122, but both plates are insulated from the cap plate 69^a.

55 To the plate 122 is connected by the screw 123, the bar 124 and this leads to the screw 125 which is insulated from the housing 68^a by the insulator 126 and provided with the clamp nut 127 to connect the wire 128.

60 The needle 39^a has mounted rigidly thereon the insulating block 129 in which is pivoted the contact plate 130 the points 131 and 132 of which alternately connect the opposing pairs of pins 113 and 116 as the needle 65 is slightly rotated on the post 37^a and as

either pair of pins is connected the electrical circuit is completed and the marine mine fired and exploded.

It is obvious that many changes may be made in the construction as set forth without departure from the merit of the invention.

What I claim as new and desire to secure by Letters Patent, is:—

1. In a firing instrument for marine mines, two magnetized bodies arranged one above the other, each of said bodies mounted to rotate around an approximately vertical axis, and a pair of electrical circuit closing contact members arranged so that a movement of either of said bodies in a rotary direction with respect to said axis will connect said contacts and close the electrical circuit.

2. In a firing instrument for marine mines, two magnetized bodies arranged one above the other, said bodies mounted to rotate around an approximately vertical and common axis, and electrical circuit closing contacts arranged so that a movement of either of said bodies in a rotary direction will connect said contacts and close said electrical circuit.

3. In a firing instrument for marine mines, two compass needles arranged one above the other, said needles normally alining in approximately parallel directions, and electrical circuit closing contacts arranged so that when the alinement of said needles is disturbed said contacts will connect and close the electrical circuit.

4. In a firing instrument for marine mines, two compass needles arranged one above the other, said needles contained in a vessel, said needles submerged in liquid, said needles normally alining in approximately parallel directions, and electrical circuit closing contact members connecting through suitable connections to said needles so that when the needles are forced from alinement said contact members will connect and complete the electrical circuit.

5. In a firing instrument for marine mines, a lower magnetic needle with north and south poles, the north pole of said needle normally pointing approximately north, an upper magnetic needle with north and south poles, said upper needle positioned over said lower needle but close enough to said lower needle so that the magnetic force from said lower needle will cause the normal north pole of said upper needle to point approximately south, and contact members so arranged that a slight rotation of either needle in either direction will connect said contact members and complete an electrical circuit.

6. In a firing instrument for marine mines a containing bowl, a post near the bottom of said bowl and extending upwardly, a lower compass needle mounted on said post, a lower stem projecting upward from said

- needle, a post mounted on said lower stem, an upper compass needle mounted on said post, a frame extending upward from said lower stem and above said upper needle, 5 an upper stem extending upwardly from said upper needle and through said frame and forming a rotary bearing in said frame and forming a rotary bearing rigidly supported by said bowl, a contact member with 10 two arms thereof spaced radially apart, a contact member on said frame, each of said contact members being in electrical connection with one wire of an electrical circuit, and said contacts being separated electrically by insulating material so that said 15 needles may rotate in opposite directions and said arms contact with said contact member when said needles are effected by magnetic influence.
- 20 7. In a firing instrument for marine mines, a pair of compass needles adjacently mounted, one of said needles pointing approximately north, the remaining needle pointing approximately south, means to support said 25 needles, a pair of contact members, each of said contact members connected through suitable connections to one of said needles, and said contact members forming the meeting terminals of an open electrical circuit so 30 that when said needles are effected by magnetic influence said needles will rotate in opposite directions and connect said contact members and close the electrical circuit.
8. In a firing instrument for marine mines, a supporting structure, a lower post carried by said structure, a lower compass needle mounted on said post, a stem rising from said lower needle, an upper post carried by said stem, an upper needle mounted on said upper post, a contact member connected by suitable connections to said stem, a contact member connected by suitable connections to said upper needle, and said contact members each forming a connectible member of an open electrical circuit so that magnetic influence will rotate said needles in opposite directions and connect said contact members and close the electrical circuit.
9. In a contact making device, two magnetized bodies arranged one above the other, 50 said bodies mounted to rotate around an approximately vertical and common axis, and electrical circuit closing contacts arranged so that a movement of either of said bodies in a rotary direction will connect said contacts and close said electrical circuit.
10. In a contact making device, two magnetized bodies arranged one above the other, 55 said bodies being mounted to permit relative rotation around an approximately vertical and common axis, and electrical circuit closing contacts arranged so that relative movement of said bodies in a rotary direction will connect said contacts and close the electrical circuit.
